STRIP-TENSIONING MEANS FOR SEWING MACHINES

Charles S. Thompson, Elmhurst, and Frank A. Kucera and Albert S. Riviere, Chicago, Ill., assignors to Union Special Machine Company, Chicago, Ill., a corporation of Illinois

Application November 6, 1937, Serial No. 173,078

8 Claims. (Cl. 112—152)

This invention relates to means useful more particularly with sewing machines, for maintaining binding or edging strips under tension as they are passed to the stitch-forming instrumentalities of such machines for attachment to the edges of the body fabrics of garments, etc.

The chief aim of our invention is to make it possible to maintain a binding strip uniformly taut and under a predetermined degree of constant tension, so that upon relaxation of the strip after it is secured to the body fabric, a smooth and undistorted edge finish is assured. This desideratum we attain as hereinafter more fully disclosed through provision of a tensioning unit 15 wherein the tensioning function is shared by a main tensioning element and a supplemental tensioning element through which the strip is horizontally passed in succession in upright position and both of which are accessible from 20 above for convenience of ready insertion of the strip initially, said main tensioning element including a pair of opposing clamp members subject to regulatable spring pressure, and said supplemental element being in the form of an upright double-tined rotatably-adjustable fork which is spaced from said main device and supported by one of the component members of the latter.

In connection with strip tensioning means 30 characterized as above, we further aim to provide simple and reliable means for controlling the clamp members of the main tensioning element so that the tension on the strip may be relieved when desired or required without necessitating 35 stoppage or slowing down of the sewing machine.

Additional objects and advantages of our invention will appear from the following detailed description of the attached drawings, wherein

Fig. I shows in side elevation, a sewing machine 40 with strip tensioning means conveniently embodying the present improvements.

Fig. II shows the organization in plan, with the needle arm of the sewing machine broken away.

Fig. III is a fragmentary sectional view taken 45 as indicated by the arrows III—III in Figs. I and II and drawn to a larger scale to more clearly show the details of our improved strip tensioning means; and

Fig. IV is a perspective view of a guide element 50 which forms a part of the strip tensioning means.

The sewing machine herein illustrated is of a well known flat bed type suitable for securing a binding strip to the edge of a body fabric B, the machine having two needles N and N', a looper 55 L and a cover thread laying finger L' which coop-

erate in forming a double chain stitch seam such as conventionally indicated at C in Fig. II to secure the strip as the body fabric is intermittently advanced across the work plate P of the machine by the feed dog indicated in dotted lines 6 at D in Fig. II. As shown, the strip S is passed horizontally along the front side of the machine in upright position and traverses a suitably-supported folder F whereby it is doubled longitudinally. The illustrated folder may be of the construction disclosed in a copending application, Serial Number 67,028 filed by us on March 4, 1936, by which the strip S is delivered around the edge of the body fabric B immediately in advance of the needles N, N' of the sewing machine, with its 10 fold margins lying perfectly flat against the opposite faces of said fabric.

The strip tensioning means which constitutes the subject of our present invention is comprehensively designated by the numeral 1 in Figs. 20 I—III of the drawings. As shown it includes a main tensioning element formed by a pair of vertically-arranged clamp plates 2 and 3 between which the strip S passes enroute to the folder F and the stitch-forming instrumentalities of the 25 sewing machine. The plate 2, it will be noted, extends well below the plate 3 and is secured near its lower edge to the front side of the sewing machine frame by a pair of screws 4. Projecting outwardly from the center of the movable clamp 30 member 3 is a headed stud 5 whereof the shank loosely fits the notch 6 at the upper end of a vertical supporting arm 7 so that said plate is free to adapt itself to the fixed clamp plate 2. At its lower end, the arm 7 loosely engages the shank 35 of a headed screw stud 8 which is threaded axially into the head of a screw stud 9 which is in turn threaded into the lower part of the clamp plate 2. By virtue of this arrangement, the arm 7 is supported by the screw stud 8 with capacity 40 for universal movement. The clamp member 3 is held against rotation about the axis of the stud 5 by a projecting stud 10 thereon which extends through a hole of slightly larger diameter in said arm. At its mid-point, the arm 7 has an outwardly-projecting boss 11 which is axially apertured to clear a guide stem projecting forwardly from the fixed clamp plate 2. Interposed between the arm 7 and a finger nut 13 at the outer threaded end of the stem 12 is a helical compression spring 15 by action of which the movable clamp member 3 is yieldingly urged toward the fixed clamp member 2 to impose frictional restraint upon the binding strip S. By adjusting the finger nut 13, the pressure of the spring 15 55

may be increased or decreased to vary the drag imposed on the strip S, and the tensioning device adapted for operation upon binding strips of different textures and characteristics. The jam nut 16 shown at 16 serves to secure the finger nut 13 against accidental displacement after adjustment. In order that the strip S may be relieved of tension when desired or required, there is provided a curved finger 17 with a cam bevel 18 at its free end adapted to coact with a rounded lug projection 19 at the back of the arm 7, said finger being fulcrumed to swing on the stud 9 as an axis. Thus when the finger 17 is moved counter-clockwise in Fig. I, its cam bevel 18 encounters the lug projection 19 on the arm 7, with the result that the clamp member 3 is moved away from the clamp member 2 in opposition to the force of the spring 15. Normally the finger 17 is held in its inactive position shown in Fig. I by a tension spring 20, with the tail projection 21 thereof against a fixed stop 22 on the plate 2. The tension release finger 17 may be operated by any suitable means, for example, through a wire connecting link 23, by a foot treadle or any lever, not illustrated, the movement of said finger being limited by another fixed stop 24 on the clamp plate 2.

Disposed substantially in the plane of meeting of the plate components 2 and 3 of the main tensioning element and supported by a horizontal arm 25 integrally formed with the plate 2 below the path of travel of the strip S is the supplemental tensioning device 26. As shown, the device 26 is in the form of an upright fork with spaced tines 27 and 28 between which the binding strip S passes prior to entering between the plates 2 and 3 of the main tensioning element. The tine 27 is fixed in a collar 29 rotatably adjustable about the tine 28 which, in turn, is anchored at the bottom in a lug 30 at the end of the bracket arm 25, said collar 29 being fixable in adjusted positions by a set screw 31.

Also embodied in the tensioning means 1 is a guiding element 32 which is relied upon to hold the strip S to a predetermined level of travel. As shown in Fig. IV, this guide element 32 is of angle configuration with a vertical slit 33 in one of its flanges to receive the strip S and a vertical slot 34 in the other of its flanges for passage of the shank of a headed screw 35 by which it is secured with capacity for up and down adjustment to a projection 36 on the plate member 2.

Due to being constructed and arranged as described, the main and supplemental tensioning elements and the guide element are all accessible for convenience of initial insertion of the strip from above which obviously is highly advantageous in practice from the stand-point of time saving. The tensioning means of our invention is moreover advantageous in that the main and supplemental tensioning elements are separately adjustable, so that on the one hand, any desired normal tension can be predetermined for the strip, while, on the other hand, control of the strip is had during periods of release of the main tensioning element through maintenance of a lesser tension on said strip by the supplemental tensioning element.

Having thus described our invention, we claim:

1. Strip tensioning means for sewing machines, including a fixed clamp member and an opposing clamp member between which the strip is passed horizontally upright enroute to the stitch-forming instrumentalities of the sewing machine, a vertical arm to the upper end of which the mov-

able clamp member is attached, means on the fixed clamp member to which the lower end of the arm is loosely connected with capacity for universal pivotal movement, a guide stem on said fixed component projecting through an opening intermediate the ends of the arm, both said pivotal connection and said stem being below the path of travel of the strip so that the clamp members are accessible from above for convenience of initially inserting the strip between them, and a helical spring in compression between a regulating nut on the outer end of the stem and the arm whereby the movable clamp member is yieldingly urged toward the fixed clamp member.

2. Strip tensioning means for sewing machines including a fixed clamp member and an opposing clamp member between which the strip is passed horizontally upright enroute to the stitch-forming instrumentalities of the sewing machine, a vertical arm to the top end of which the movable clamp member is attached, a stud projection on the fixed clamp member to which the lower end of the arm is loosely connected below the path of travel of the strip with capacity for universal pivotal movement, a spring for urging the movable clamp member toward the fixed clamp member, a cam finger fulcrumed on the pivot stud for the arm and adapted to coact with said arm to effect withdrawal of the movable clamp member away from the fixed clamp member in opposition to the spring to relieve the tension on the strip, and means for actuating the cam finger.

3. Strip tensioning means for sewing machines comprising a pair of opposing clamp elements between which the strip is passed horizontally upright enroute to the stitch-forming instrumentalities of the sewing machine, means whereby the clamp elements are connected together below the path of travel of the strip so as to be accessible from above for convenience of initially inserting the strip between them, and a slotted guide likewise open from above for determining a definite level of travel for the strip, said guide being vertically adjustable on one of said clamp members.

4. Strip tensioning means for sewing machines, including a fixed clamp member and an opposing clamp member between which the strip is passed horizontally upright enroute to the stitch-forming instrumentalities of the sewing machine, a vertical arm to the upper end of which the movable clamp member is attached, means on the fixed clamp member to which the lower end of the arm is loosely connected with capacity for universal pivotal movement, a guide stem on said fixed component projecting through an opening intermediate the ends of the arm, both said pivotal connection and said stem being below the path of travel of the strip so that the clamp members are accessible from above for convenience of initially inserting the strip between them, a helical spring in compression between a regulating nut on the outer end of the stem and the arm whereby the movable clamp member is yieldingly urged toward the fixed clamp member, and treadle means whereby the arm may be actuated to relieve the tension on the strip or to open the clamp for initial insertion of the strip.

5. Strip tensioning means for sewing machines comprising a pair of opposing clamp elements between which the strip is passed horizontally upright enroute to the stitch-forming instrumentalities of the sewing machine, means whereby

- the clamp elements are connected together below the path of travel of the strip so as to be inaccessible from above for convenience of initially inserting the strip between them, and a slotted guide 5 likewise open from above for determining the level of travel of the strip between the aforesaid clamp elements, said guide being secured, with capacity for vertical adjustment, to one of the clamp elements.
- 10 6. Strip tensioning means for sewing machines comprising a main tensioning device with a pair of opposing clamp members between which the strip is passed horizontally upright enroute to the stitch instrumentalities of the sewing machine, and means whereby said clamp members are 15 yieldingly connected together below the path of travel of the strip so as to be accessible from above for convenience of initially inserting said strip between them, and a vertical fork-like supplemental tensioning device positioned beyond the main tensioning device and likewise open from above, said supplemental device including a pair of tines whereof one is fixed in a collar which is rotatively adjustable about the other tine for 20 the purpose of varying the tensioning induced in the strip, the last mentioned tine being supported by one of the clamp members of the main tensioning device.
7. Strip tensioning means for sewing machines comprising a main tensioning device with a pair of opposing clamp members between which the strip is passed horizontally upright enroute to the stitch instrumentalities of the sewing machine, and means whereby said clamp members are 25
- yieldingly connected together below the path of travel of the strip so as to be accessible from above for convenience of initially inserting said strip between them, a rotatively adjustable vertical fork-like supplemental tensioning device beyond the main tensioning element and likewise open from above, and an intermediately-positioned vertically-adjustable slotted guide similarly open from above for determining the level of travel of the strip through the main and supplemental tensioning device said supplemental tensioning device and guide being both supported by one of the members of the main tensioning device. 10
8. Strip tensioning unit for sewing machines comprising a main tensioning device and an aligned auxiliary tensioning device beyond said main tensioning device each having a pair of components between which the strip is passed horizontally upright enroute to the stitch forming instrumentalities of the sewing machine and each being accessible from above for convenience of initially threading the strip; an intermediately positioned vertically-adjustable slotted guide similarly open from above for determining the level 15 of travel of the strip through the main and auxiliary tensioning devices; and a common support for said main and auxiliary tensioning devices and the guide, removably secured to the sewing machine. 20
